(57) CLAIM

The ornamental design for a bed as shown and described.

DESCRIPTION

FIG. 1 is a perspective view of a bed, showing a first embodiment of my new design;

FIG. 2 is a first side view of the bed of FIG. 1.

FIG. 3 is a second side view of the bed of FIG. 1.

FIG. 4 is a front view of the bed of FIG. 1.

FIG. 5 is a rear view of the bed of FIG. 1.

FIG. 6 is a top view of the bed of FIG. 1.

FIG. 7 is a bottom view of the bed of FIG. 1.

FIG. 8 is a perspective view of a bed, showing a second embodiment of my new design;

FIG. 9 is a first side view of the bed of FIG. 8.

FIG. 10 is a second side view of the bed of FIG. 8.

FIG. 11 is a front view of the bed of FIG. 8.

FIG. 12 is a rear view of the bed of FIG. 8.

FIG. 13 is a top view of the bed of FIG. 8.

FIG. 14 is a bottom view of the bed of FIG. 8.

FIG. 15 is a perspective view of a bed, showing a third embodiment of my new design;

FIG. 16 is a first side view of the bed of FIG. 15.

FIG. 17 is a second side view of the bed of FIG. 15.

FIG. 18 is a front view of the bed of FIG. 15.

FIG. 19 is a rear view of the bed of FIG. 15.

FIG. 20 is a top view of the bed of FIG. 15.

FIG. 21 is a bottom view of the bed of FIG. 15.

FIG. 22 is a perspective view of a bed, showing a fourth embodiment of my new design;

FIG. 23 is a first side view of the bed of FIG. 22.

FIG. 24 is a second side view of the bed of FIG. 22.

FIG. 25 is a front view of the bed of FIG. 22.

FIG. 26 is a rear view of the bed of FIG. 22.

FIG. 27 is a top view of the bed of FIG. 22; and,

FIG. 28 is a bottom view of the bed of FIG. 22.

Portions of the bed shown in broken lines form no part of the claimed design.

1 Claim, 24 Drawing Sheets
